MUFFLER OR THE LIKE

Lillian Small, 320 S. Franklin St., Chicago, Ill.

Filed June 17, 1959, Ser. No. 56,390

Term of patent 14 years

(Cl. D3—16)

FIG. 1 is a plan view of a muffler or the like arranged in extended position showing my new design.

FIG. 2 is a front view of the muffler or the like folded in a position for wearing showing my new design.

FIG. 3 is a rear view of the muffler or the like shown in FIG. 2.

I claim:

The ornamental design for a muffler or the like, substantially as shown.
